CLAIM

The ornamental design for a under body sprayer as shown and described.

DESCRIPTION

FIG. 1 is a front perspective view of the under body sprayer showing my new design;

FIG. 2 is a top plan view thereof;

FIG. 3 is a bottom plan view thereof;

FIG. 4 is a front plan view thereof;

FIG. 5 is a rear plan view thereof;

FIG. 6 is a side elevation view thereof;

FIG. 7 is the other side elevation view thereof; and,

FIG. 8 is an environmental perspective view of FIG. 1.

The details shown in broken or discontinuous lines in the accompanying drawings are to be disregarded when considering the overall impression of the design.
